[57] CLAIM

The ornamental design for a tub shell or the like, as
shown and described.

DESCRIPTION

FIG. 1 is a perspective view taken from the top, left,
and front of a tube shell or the like showing my new
design;

FIG. 2 is a second perspective view taken from the top,
right, and front thereof on an enlarged scale;

FIG. 3 is a top plan view thereof on an enlarged scale;
FIG. 4 is a front elevational view thereof on an enlarged
scale;

FIG. 5 is a rear elevational view thereof on an enlarged
scale;

FIG. 6 is a bottom plan view thereof on an enlarged
scale;

FIG. 7 is a right side elevational view thereof, the left
side elevational view being the mirror image thereof on
an enlarged scale;

FIG. 8 is a cross-sectional view taken on line 8—8 of
FIG. 3;

FIG. 9 is a cross-sectional view taken on line 9—9 of
FIG. 3; and
